(No. Model.)

F. H. TOBIAS.

FOLDING BEDSTEAD.

No. 329,101.

Patented Oct. 27, 1885.

Fig. 1.

Fig. 3.

This technical drawing illustrates a cabinet or shelving unit with a total of 12 vertical compartments. The compartments are labeled as follows: the leftmost compartment is labeled 'n' at the top and 'f' at the bottom; the second compartment from the left is labeled 'g' at the top and 'f' at the bottom; the third compartment is labeled 'a' at the top and 'd' at the bottom; the fourth compartment is labeled 't' at the top and 'i' at the bottom; the fifth compartment is labeled 'k' at the top and 'u' at the bottom; the sixth compartment is labeled 'g' at the top and 'f' at the bottom; the seventh compartment is labeled 'g' at the top and 'f' at the bottom; the eighth compartment is labeled 'n' at the top and 'f' at the bottom; the ninth compartment is labeled 'n' at the top and 'f' at the bottom; and the rightmost compartment is labeled 'b' at the top and 'i' at the bottom. The top of the cabinet features a horizontal bar with the text 'PRESSURE' and 'FREQUENCY' written on it. The bottom of the cabinet has a horizontal bar with the text 'K' and 'M' written on it. The entire unit is supported by a base with legs.

UNITED STATES PATENT OFFICE.

FRANCIS H. TOBIAS, OF NEW YORK, N. Y.

FOLDING BEDSTEAD.

SPECIFICATION forming part of Letters Patent No. 329,101, dated October 27, 1885.

Application filed October 6, 1884. Serial No. 144,778. (No model.)

To all whom it may concern:

Be it known that I, FRANCIS H. TOBIAS, of the city, county, and State of New York, have invented a new and useful Improvement 5 in Folding Bedsteads; and the following is declared to be a description of the same.

Folding bedsteads are generally made either hinged at one end rail to a fixed case, into which the bed folds, or the bed is divided 10 into halves and folds together, and into a fixed case.

My invention relates to a folding bedstead or crib wherein the side rails and end rails are fixed together and mounted on rollers, 15 which rollers are fastened to the side rails and to one end rail, and slide in ways, one set of ways being horizontal and the other set perpendicular.

The bed-bottom folds up into a fixed case, 20 and said case is made with front doors, and, by preference, an open back for ventilation, &c., and upon the inner surface of the front doors are a portion of the horizontal ways, said doors acting as a support for the bed when 25 opened out to place.

In the drawings, Figure 1 is a vertical cross-section of my folding bedstead. Fig. 2 is a plan of the same, and Fig. 3 is a vertical cross-section of the bedstead closed.

The fixed case is composed of the side pieces, *a a'*, back pieces, *b b'*, and front doors, *c c'*, and the bed-bottom is composed of the 30 end rails, *d d'*, side rails *e e'*, hinged side rails *f f'*, and slats *g*.

Upon the side pieces, *a a'*, are the fixed 35 slideways *h h'*, and there are rollers *i* upon each end of the hinged side rail *f'*, that move up or down in these slideways *h h'* as the bedstead is opened or closed.

There are horizontal slideways *k k'* in two 40 parts, one part being secured to the side pieces, *a a'*, and the other part being secured upon the inner surface of the folding doors *c c'*, and there are rollers *l* upon the end rails, *d d'*, at the center thereof, and these rollers *l* move back and forth in the slideways *k k'*. There are openings in the side pieces *a a'*, 45 into or through which the ways *k k'* are received when the folding doors are closed.

To close the bed, the bed-bottom portion

is tilted and pushed back into the fixed case, as shown in Fig. 3, the rollers *l* running horizontally upon the ways *k k'*, and the rollers *i* running down perpendicularly between the ways *h h'*, and the side rails *f f'* closing 55 against the bed. The folding doors can then be closed.

In opening the bed the folding doors are opened out at right angles to the case, and the bed-bottom pulled out upon the ways *k k'*, and in so doing the side rail *f'* is raised vertically, its rollers being between the ways *h h'*, and the rollers running out upon the ways *k k'*.

When the bed-bottom is drawn out for use, 65 it may be held from tipping by a bolt or secured in place in any desired manner. The folding doors *c c'* are hinged at *m* to the side pieces, *a a'*, and the side rails, *f f'* and *e e'*, are hinged together at *n*.

Instead of the folding doors *c c'*, the bottom of the bedstead may be paneled to form 70 a front to the fixed case, and the slideways *k k'* may be formed by hinged brackets, that are adapted to fold in against the case, and in this 75 connection an adjustable leg should be used to support the bracket and fixed case when the bed is opened.

The bedstead-case may be provided with 80 casters, if desired, and the rollers *i* and *l* should be grooved to fit the ways *h h'* and *k k'*. Sliding blocks grooved to fit said ways may be substituted for the rollers or for any number of them.

I claim as my invention—

1. In a folding bedstead, the combination, 85 with a tilting bed-bottom and rollers upon the same, of the fixed case having the side pieces, *a a'*, back pieces, *b b'*, hinged front doors, *c c'*, and the slideways *h h'* and *k k'*, substantially as set forth.

2. In a folding bedstead, the combination, 90 with a fixed case having hinged front doors, and slideways upon the respective parts, of the bed-bottom composed of the end rails, *d d'*, side rails *e e'*, hinged side rails *f f'*, and slats *g*, and the rollers *i* upon the ends of the side rails *f'*, and the rollers *l* upon the end rails, *d d'*, substantially as set forth.

3. In a folding bedstead, the combination, 95

with a fixed case, hinged front doors, and folding bed-bottom, of the slideways $h\ h'$, placed perpendicularly upon the sides of the fixed case, and the slideways $k\ k'$, placed horizontally upon the hinged front doors and sides of the fixed case, respectively, and the rollers l and i between the respective slide-ways $k\ k'$ and $h\ h'$, substantially as and for the purposes set forth.

Signed by me this 2d day of October, A. D. 1884.

F. H. TOBIAS.
